[57] CLAIM

The ornamental design for a fishing pole latching storage apparatus, as shown and described.

DESCRIPTION

FIG. 1 is a perspective view of a new design for a fishing pole storage apparatus, the apparatus being shown in a pole access position;

FIG. 2 is a front elevational view of the apparatus in pole storage position, the ghost line portions being for the purpose of environment only;

FIG. 3 is a top view of the apparatus in pole storage position; FIG. 4 is a left side view of the apparatus in pole storage position;

FIG. 5 is a right side view of the apparatus in pole storage position;

FIG. 6 is a bottom view of the apparatus in pole storage position; and,

FIG. 7 is a rear elevational view of the apparatus in pole storage position, the ghost line portions being for the purpose of environment only.
